UNITED STATES PATENT OFFICE.

JOHN MILLAR, OF KEARNEY, NEW JERSEY.

SIGNALING.

SPECIFICATION forming part of Letters Patent No. 773,025, dated October 25, 1904.

Application filed October 22, 1902. Serial No. 128,275. (No model.)

To all whom it may concern:

Be it known that I, JOHN MILLAR, a subject of the King of Great Britain and Ireland, and a resident of Kearney, county of Hudson, and

5 State of New Jersey, have invented certain new and useful Improvements in Signaling, of which the following is a specification.

10 My invention relates generally to signaling, and has more particularly reference to electric semaphores.

15 Electric semaphores at the present time are usually operated by a motor to move the signal-arm from the danger or stop position to the clear position or, if it be a three-position signal, to "caution" and then to "clear." When in either position, the signal is controlled by a slot in the form of an electromagnet adapted to be energized and deenergized by the movement of trains over the tracks controlling an armature operating a suitable locking and releasing device. The return movement of the signal-arm to "danger" is effected by gravity, the slot releasing the signal when its magnet is deenergized by a train entering a 25 certain block or section.

It sometimes occurs that the armature refuses to move away from the electromagnet when the latter is deenergized, so that the signal is not free to drop by gravity. This 30 adhesion of the armature to the magnet may be caused by frost or it may be due to the magnetization of the armature. When a condition of this character arises, the signal is effectually locked in the clear or caution position and cannot return to the danger position. The seriousness of such a state of affairs will be readily understood; and the chief object of my invention is to produce a device whereby when this improper adhesion takes 35 place the armature will be automatically forced away from the magnet and the semaphore restored to "danger" by the motor and whereby also the apparatus will be put in perfect working order again. The electric 40 semaphore, as just described, serves to illustrate the objections which can be raised against all semaphores in use at the present time, whether they be all electric, electropneumatic, or all pneumatic. In other words, 45 there is no semaphore-signal at the present

time which will be restored to "danger" by means of a motor, whether such motor be in the form of an electric motor or an air-pressure device.

As has been stated, the chief object of my 55 invention is to overcome this objection.

Other objects will appear as the specification proceeds.

I shall describe a semaphore, together with adjunctive and auxiliary devices relating to 60 the same, embodying my invention and afterward point out the novel features in the claims.

In my signal the slot-magnet is mounted on a pinion or gear segment, which engages 65 with a rack on the signal-rod. This pinion is in engagement with the rack on the rod at all times, so that an unbroken connection is maintained. The said pinion carries an arm or extension provided with a locking and releasing device controlled by the armature of the magnet. This locking and releasing device, together with the electromagnet and other means hereinafter more fully described, forms what I shall term a "double-lock slot." 75 Adjacent to the slot-magnet and the rack of the signal-rod there is located a driving-gear having a pin or other means for engaging with an escapement-lock on the mechanical member of the slot. This driving-gear is 80 placed eccentric with relation to the pinion of the slot.

The motor is started up at the proper time by the passage of a train over the tracks from one block to another, thereby rotating the 85 driving-gear. Simultaneously with this the slot-magnet is energized. The rotation of the driving-gear causes the pin carried by the same to contact with a primary locking device on the mechanical member of the slot, 90 which moves the armature into contact with the slot-magnet and also moves the escapement-lock of the slot into its locked position. The adhesion of the armature to the magnet prevents the primary locking device of the 95 mechanical member from moving back, and thus keeps the escapement-lock controlled by same in its locked position, so that when the pin of the driving-gear reaches the said escapement-lock of the slot it will carry the 100

latter with it as it rotates, thereby rotating the pinion meshing with the rack on the signal-rod, and thus drive the signal to the clear position. If the slot-magnet is not energized, the pin on the driving-gear will escape past the escapement-lock on the slot and the signal will remain in the danger position.

Owing to the eccentricity of the driving-gear with relation to the slot-pinion the pin 10 on the said gear escapes by the escapement-lock of and releases itself from the mechanical member of the slot at a certain point, while the said mechanical member engages with retaining means for maintaining it in the 15 position to which it has been carried. The movement of the signal-rod cuts off the motor, stopping its rotation. A train entering the block controlling the signal will deenergize the slot-magnet, and the mechanical member 20 of the slot will free itself from the retaining means, whereby the signal will be at liberty to drop by gravity, and thus to return to "danger."

The signal-rod is provided with two opposed 25 racks, one of which has already been noted as engaging with the slot-pinion. The other of these two opposed racks engages with a restoring-pinion carrying a restoring-arm. When a train enters the block and deenergizes 30 the slot-magnet, causing the signal to be free to return to "danger" by gravity, it also puts the motor in circuit. If the signal returns to "danger," the movement of same will cut the motor out of circuit again, thus preventing it 35 from starting up; but if the armature should fail to leave the slot-magnet when the latter is deenergized, and thereby prevent the signal from being free to drop by gravity, the motor will start up and the pin or other en- 40 gaging means on the driving-gear will come in contact with the restoring-arm, carrying the same with it and causing the restoring-pinion, which engages with the other of the two opposed racks on the signal-rod, to move 45 the latter down. The movement of the signal-rod will cause the first of the opposed racks to turn the slot-pinion, thus forcing the armature away from the magnet, so as to release the mechanical member of the slot from 50 the retaining means, and in that way to restore the signal-arm to "danger" and also to restore the slot to its proper position and the parts to their normal working condition. As soon as the parts are restored the motor is 55 cut out of circuit by the action of the signal-rod, thus stopping the said motor. The movement of the driving-gear to carry the signal from "danger" to "clear" is equal to half a revolution of the same. When a three-po- 60 sition signal is used, there will be two retaining means for the mechanical member of the slot, the first for the caution position and the second for the clear position. In that case the driving-gear will have two pins, one 65 of which is nearer its center than the other,

and will carry the slot a distance of a quarter of a revolution, when the first pin will escape past the escapement-lock of the slot and the motor stop. When the motor is started up again by the action of the train in the suc- 70 ceeding block, the second pin of the driving-gear will carry the slot another quarter of a revolution and then escape, leaving the signal in the clear position. The return move- 75 ment to "danger" is then effected either by gravity or by the restoring device, as previously explained. When a two-arm signal is used, another slot and restoring mechanism is provided on the other side of the driving-gear, which latter is made to serve for both 80 signal-arms. Only one pin on the driving-gear on each side will then be used. In this case, however, the restoring-arm is provided with a magnet and a spring to move it into and out of the path of the pin carried by the 85 driving-gear at the proper time, as otherwise the rotation of the gear to operate one signal-arm would interfere with the other signal-arm. The mechanical member of the slot is constructed in the same way as in connection 90 with the one-arm signal, as the slot will not be carried around with the pin on the gear unless locked by the action of the slot-magnet. Other features of construction and improved combinations and arrangement of parts will 95 be more fully described in the detailed description which follows.

The present application is a sister application to one filed on the 22d day of October, 1902, Serial No. 128,274, covering my invention broadly and covering also specifically a three-position signal, and is intended to cover the construction of a two-position signal of both the one-arm and the two-arm type. 100

In the drawings I have embodied my invention in a suitable form; but changes may of course be made within the scope of the claims.

In the said drawings, Figure 1 is a general view of a signal embodying my invention. Fig. 2 is an enlarged view of the driving-gear, slot, connection for the signal-rod, and supplementary devices, showing the parts in the position occupied by them when the signal is at "danger" and when the slot-magnet is deenergized, another slot mechanism being indicated in dotted lines back of the driving-gear. Fig. 2^a is a sectional view through the escapement-lock on the line *z* of Fig. 3. Fig. 3 is a side view of Fig. 2. Fig. 4 is a detail view of the ordinary restoring mechanism. Fig. 5 is a detail view of the restoring-arm used on the two-arm signals. Fig. 6 is a diagrammatic view showing the signals in three blocks and the wiring and circuits used in connection with my invention. 115

Similar letters of reference indicate corresponding parts in the different views.

A is a motor having a non-reversible armature and provided with the armature-shaft *a'*. *F* indicates a signal-rod to which the mo- 120 125 130

tion of this motor is imparted at the proper times through the instrumentality of suitable means, as the driving-gear C and the slot E. The signal-rod carries a semaphore of the usual construction, counterweighted so as to have a bias to danger position. The driving-gear C will preferably be in the form of a worm-gear receiving its motion from the worm B, mounted on the shaft b', which is coupled to the armature-shaft a' by means of the coupling b³. Suitable means for supporting the driving-gear C is provided in the form of a bushing c³ of the framework d', which rises on both sides of the said driving-gear from the base D. In the present form the semaphore will conveniently be operated through one of two opposed racks f' and f², whose faces turn away from each other, attached to the signal-rod F. To correspond with this construction, a pinion or gear segment e' is provided. The slot mechanism as a whole is indicated by the reference-letter E and is conveniently carried by the said pinion e', which carries a rigidly-fixed arm and extension e⁴, provided at its upper end with the cross-piece e⁵, which forms a support for mounting the different parts of the slot. The slot proper comprises an escapement-lock e⁹, mounted on the pivot e⁶⁰ of the cross-piece e⁵ and normally held yieldingly by means of the clock-spring e¹⁴. To transfer the motion of the driving-gear to suitable mechanism or means for operating the signal-rod, such as the pinion e' and the rack f', I provide a pin c' on the said gear and attach a projection e¹⁰ on the said escapement-lock, with which the said pin is adapted to engage. The pinion e' is mounted eccentric with relation to the gear C for reasons which will hereinafter appear. e² is the slot-magnet, conveniently mounted on the pinion e' and controlling the armature e³, mounted loosely on one side of the pin e⁶. The escapement-lock is further provided with a notch e¹¹, with which engages the dog e¹⁹, also loosely mounted on the pin e⁶, so as to move independently of the armature. This dog has the effect when the magnet is energized of holding the escapement-lock rigidly by engaging in the notch e¹¹ of the latter, so that when the gear C turns and the pin c' engages with the projection e¹⁰ the pinion e' will receive the motion of the said gear, thereby operating the signal-rod. To prevent undue movement of the escapement-lock, the latter is provided with a stop e¹², engaging with the pin e¹³ on the extension e⁴. e¹⁵ is a retaining-lock in the form of a member e¹⁶, mounted on the pivot e⁶¹ of the escapement-lock e⁹ and carrying the yielding projection e¹⁷ by the spring e¹⁸. G is a notched standard with which the said retaining-lock will engage when the pinion e' has been turned a sufficient distance. At that point the pin c' will escape past the projection e¹⁰ of the escapement-lock owing to the eccentricity of the pin-

ion e' with relation to the driving-gear. The signal has now been moved from "danger" to "clear" and the action of the motor will therefore cease. The slot and magnet being locked, as the magnet is still energized, will prevent the return of the arm. When the next train comes along and moves into the block controlling the said signal, it will short-circuit the track-circuit and deenergize the magnet, so that the escapement-lock is no longer held in its rigid position by the dog e¹⁹, but is held yieldingly only by the spring e¹⁴. The counterweight of the semaphore will therefore be free to act upon the escapement-lock, which turning upon the pivot e⁶⁰ will free the retaining-lock from the retaining means or notched standard G, thereby permitting the rack f' to drive the pinion e', carrying the slot, back to its original position. To effect the initial or primary movement of the armature into contact with the magnet, I provide a primary locking device consisting of two jaws e⁷, one of which carries the friction-roll e⁸, attached to the pivoted armature, and the intermediate member e²³, pivoted at e²⁴ and located substantially at right angles to the armature and engaging with the jaws e⁷ of the same by means of the arm e²⁵ to turn the armature on the pivot e⁶.

e²⁶ is an arm moving with the member e²³ and adapted to be engaged by the pushing-pin e²⁷, which in turn is operated by the pin c' to move the armature into contact with the magnet through the above means prior to the said pin c' reaching the projection e¹⁰. If the magnet is not energized, the armature will of course move away from the same again as soon as the pin c' is past the pushing-pin e²⁷, so that the escapement-lock will not be held rigidly by the dog e¹⁹, thereby allowing the said pin c' to escape past the projection e¹⁰. The dog e¹⁹ is controlled by the armature by means of the cam e²² moving with the intermediate member e²³, on which cam rests the roll e²¹ of the arm e²⁰, moving with the dog e¹⁹. In this way the armature and magnet will control the dog e¹⁹ through the escapement-lock e⁹, so that after the magnet is energized and the armature has been moved into contact with the same the connection between the driving-gear and the means for operating the signal-rod is controlled absolutely by the said magnet and armature and the slot cannot be released except by deenergizing the magnet. The reason for using this double-lock slot is to distribute the strain more evenly. If, for instance, the dog e¹⁹ and the armature e³ were mounted so as to move in unison by being both fast on the pin e⁶, the strain would fall on this pivot only. By interposing the intermediate member e²³ and arm e²⁰ I can get the benefit of two levers, which tends to distribute the strain. G' is a notched standard placed a distance away from the danger position of the slot

substantially equal to a semicircle, forming retaining means to engage with the retaining-lock on the slot.

H is a restoring device in the form of a pinion h' , engaging with the rack f^2 of the signal-rod and provided with an arm or member, as h^2 , which is moved into the path of the pin c' when the signal is in the clear position and out of the path of the pin when the slot is restored to the danger position.

When a two-arm signal is used, it is convenient to operate both arms from the same motor and from the same driving-gear. To this end a second slot mechanism substantially like the one previously described is placed on the other side of the driving-gear, which latter in this instance is provided with a second pin c^2 on its other side. One modification, however, is necessary when this construction is used—viz., the restoring-arms, which must be so arranged that the driving-gear can rotate and operate one arm without interfering with the other. This is accomplished by providing the restoring-pinion h' with an arm h^3 , pivoted at its center at h^4 and held normally out of the path of the pin c' or c^2 by the spring h^5 , while it is moved into the path of the pin by the restoring-magnet h^6 at the proper moment when the said magnet is energized.

The opposed racks f' and f^2 may be carried by the signal-rod or by a connection or extension of same. In the present instance they are carried by the connection f^3 , adapted to be secured at f^4 to the signal-rod proper and connecting at its lower end with the piston-rod i' of the dash-pot I. The base D is secured removably to a hollow support d' and carries the dash-pot I, which is removably secured to the said base and projects inside the hollow support. By disconnecting the signal at f^4 and the coupling b^3 of the shafts a' and b' the entire operating mechanism can be removed and replaced, which is of great advantage.

In connection with a two-arm signal two dash-pots I will of course be used, and when the signals and armature-shaft are disconnected the base D can be turned around on the hollow support d' by sliding the said base on the track d^2 , so as to make all the parts easily accessible for cleaning and repair. To facilitate matters, the base is provided with a spring-seated pin or catch d^3 , which engages with apertures d^4 and d^5 , opposite to each other, so that when the base is turned it will stop after a half of a revolution, thereby gagging the position of the mechanisms carried upon the said base accurately.

In Fig. 6 is shown a diagrammatic view of the signals in three blocks, together with the wiring and circuits for operating the mechanisms properly, a train being indicated in the last block.

In each signal the motor is connected with the battery J at all times by the wire j' , while

the slot-magnet is connected with the said battery through the wire j^2 .

K is a relay energized by the track-circuit coming from the battery J' and controlling the finger j^3 , forming a switch connected with the battery J through wire j^4 . When the relay is deenergized, the finger j^3 is in contact with the electrode j^5 of the wire j^6 , terminating in the electrode j^7 , and when the relay is energized it attracts the finger j^3 and moves it into contact with the electrode j^8 , connecting with the slot-magnet, thereby putting the said magnet in circuit, and also with the wire j^9 , terminating in the electrode j^{10} . The finger j^{13} is connected with the motor by means of the wire j^{11} and is adapted to be operated mechanically between the two electrodes j^7 and j^{10} by the fluctuation of the signal-rod.

When the signal is at "clear," the finger j^3 will be in contact with the electrode j^8 , so that the slot-magnet is in circuit, thereby maintaining the slot locked, so that the retaining-lock e^5 is held in engagement with the notches on the standard G' while the motor is out of circuit, owing to the fact that the finger j^{13} has been moved into contact with the electrode j^7 by the fluctuation of the signal-rod F. As a train now enters the block it short-circuits the track-circuit of the battery J', thereby deenergizing the relay K, causing the arm j^3 to drop into contact with the electrode j^5 . This, it will be observed, puts the slot-magnet out of circuit, thereby releasing the slot and leaving the signal free to return to "danger" by gravity, and puts the motor in circuit. If the signal returns to "danger" by gravity, the movement of the signal-rod will cause the finger j^{13} to move into contact with the electrode j^{10} , thus putting the motor out of circuit; but if the armature refuses to leave the slot-magnet, and thereby maintains the signal in the clear position, the motor, being in circuit, will start up and the pin c' , coming in contact with the restoring-arm h^2 , will cause the pinion h' to move the signal-rod down, the power breaking the armature away from the slot-magnet, thus restoring the signal to "danger." The motor then stops, being cut out of circuit by the movement of the signal-rod as just described.

The train upon leaving the block and entering the one next succeeding causes the track-circuit to be restored, energizing the relay K, bringing the arm j^3 in contact with the electrode j^8 , thus putting both the motor and the slot-magnet in circuit. As the motor starts up, the pin c' will engage with the primary locking device, pushing the pin c^2 against the arm c^3 , thereby causing the armature to move into contact with the slot-magnet and the dog c^4 to lock the escapement-lock c^5 . As the gear C rotates, the pin c' will next engage with the projection c^6 of the escapement-lock, causing the rotation of the pinion c' and the fluctuation of the signal-rod. This movement will

continue until the signal has been driven to the clear position, when, owing to the eccentricity of the gear and the pinion carrying the projection e^0 , the pin c' will escape 5 past the latter and the retaining-lock e^5 engage with the notched standard G' , causing the signal to be maintained in the position to which it has been moved. The movement of the signal-rod F in carrying the signal from 10 "danger" to "clear" will cause the arm j^{13} to move into engagement with the electrode j^7 , thereby putting the motor out of circuit, while leaving the slot-magnet in circuit, so as to maintain the slot locked. The signal then 15 mains in this position until another train enters the block and releases the slot.

When two arms are used, the wiring just described will operate the upper or danger arm S , while the lower or caution arm is 20 controlled by a second finger, j^3 , of the relay K , one finger lying behind the other, and a second arm, like j^{13} , controlled by the movement of the signal-rod of the signal S' . A wire similar to j^6 (denoted by the reference-letter j^{60} , and provided with the electrodes j^{50} and j^{70}) is adapted to make a circuit from the second finger, j^3 , through the second arm, j^{13} , to the motor. The slot-magnet of the second arm, S' , is connected with the battery by the 25 wire j^{36} . From the motor runs another wire, j^{19} , terminating in the movable electrode j^{20} , which is adapted to move with the upper or danger arm S and when the latter is at clear to come in contact with the electrode j^{21} of the 30 wire j^{22} , connected by the wire j^{37} with the slot-magnet of the caution arm S' and terminating at its other end in the electrode or finger j^{23} . From the electrode j^{20} runs a wire j^{11} , terminating in the electrode j^{12} .

40 K' is a second relay, connected by line-wires j^{24} and j^{25} with the battery J of the succeeding block, the circuit to energize the said relay being closed through the electrodes j^{26} and j^{27} when the danger-arm S of the said succeeding 45 block moves to "clear," thereby putting the motor and the slot-magnet of the caution-arm S' in circuit to drive the said caution-arm S' to "clear." As will be remembered, when two signal-arms are used the restoring- 50 arms of the slots are provided with electromagnets h^6 . The electromagnets are both connected by the wires j^{30} and j^{31} with the electrodes j^7 and j^{70} and by means of the wires j^{32} and j^{33} with the wire j' .

55 Assuming now that both arms are in the clear position, a train on entering the block will short-circuit the track-circuit from the battery J' , thus deenergizing the relay K , causing the two fingers j^3 to move into contact with the electrodes j^5 and j^{50} . As the signal-arms are in the clear position the fingers j^3 will be in contact with the electrodes j^7 and j^{70} . The closing of the circuits at j^5 and j^{50} therefore deenergizes both slot-magnets and puts both restoring-magnets and

the motor in circuit. If the signal-arms drop by gravity, the motor and restoring-magnets will be cut out of circuit by the fingers j^{13} being moved out of contact with the electrodes j^7 and j^{70} . If they do not drop by gravity, 70 the motor will start up, and the pins c' and c^2 on coming in contact with the restoring-arms will restore the signals to the danger and caution positions, respectively, and cut the motor and restoring-magnets out of circuit again, as previously described. Likewise if either arm should fail to return to the horizontal position the motor would start up and, owing to the restoring-magnets, would drive the proper arm to its upper position. Upon 80 the train leaving the block the track-circuit will be restored, reenergizing the relay K and moving the fingers j^3 into contact with the electrodes j^8 and j^{80} , thereby putting the slot-magnet of the danger-arm S and the motor 85 in circuit, thus driving the said danger-arm to "clear." In so doing the electrode j^{20} is moved into contact with the electrode j^{21} . The slot-magnet of the caution-arm S' , however, is not put in circuit, as the relay K' 90 has been deenergized by the danger-arm in the succeeding block going to "danger," whereby the electrodes j^{26} and j^{27} are brought out of contact with each other. When the train enters the third block, the relay K' is 95 energized by the action of the danger-arm S in the second block going to "clear," thereby closing the circuit at j^{26} and j^{27} . This moves the finger j^{13} into contact with the electrode j^{23} , thus putting the slot-magnet of the caution-arm S' and the motor in circuit and driving the said caution-arm S' to "clear." From 100 this it appears that the two slot-magnets are put in circuit successively and that they are put out of circuit simultaneously and the restoring-magnets put in circuit simultaneously. 105

It will of course be understood that the system of wiring can be changed very materially so long as the motor-slots and restoring-magnets are put into and out of circuit at the proper moment. Obviously the signal can be used both on the normal danger and normal safety plan by changing the wires to correspond therewith. Instead of line-wires the so-called "wireless system" could be used. 110 The various mechanisms comprising the slot, driving-gear, motor, &c., will, as is usual, be inclosed in a suitable casing, and the signal-rod will preferably be inside a hollow iron signal-post. In place of the gear C a simple 115 disk could be used, and other engaging means instead of the pin could of course also be employed. The gear C could of course be the last in a train of gears; but the construction shown here is very much preferable, as with 120 a worm and worm-gear an even and steady movement is obtained.

125 My invention may of course also be used with an interlocking system, whether manual or power, if such should be desired. The 130

coupling for connecting the armature-shaft with the worm-shaft will preferably be a friction-clutch. The opposed racks of the signal-rod can be formed on the signal-rod 5 proper or on a connection in another plane, if so desired. Furthermore, the signal could be constructed so as always to be moved to "danger" by the motor by simply balancing the weight of the signal rod and arm. The 10 semaphore will of course carry the usual spectacles to show differently-colored lights at night.

The arm ¹³ can be constructed so that it will break the circuit for the motor as soon 15 as the armature leaves the signal, or it can be constructed so that it will not break the circuit until the semaphore-arm has assumed the horizontal position.

Having thus described my invention, what 20 I claim is—

1. In a signal, the combination with a semaphore counterweighted so as to have a bias to the "danger" position, of a motor, a slot, a slot-magnet, a restoring device operated by 25 the motor, connections and circuits for putting the slot-magnet and motor in circuit to drive the semaphore from the "danger" position to "clear," and for putting the motor out of circuit when the said semaphore arrives 30 at "clear," the slot and magnet when locked, preventing the return of the semaphore, and for putting the slot-magnet out of circuit to allow the semaphore to return to the "danger" position by gravity, and for putting the 35 motor in circuit to restore the semaphore to "danger" through the instrumentality of the restoring device in case the said semaphore is not restored to "danger" by gravity when the magnet is put out of circuit.

40 2. In a signal, the combination with a semaphore, having a "danger" and a "caution" arm, counterweighted respectively to the "danger" and "caution" positions, and a motor, of a slot, a slot-magnet, and a restoring device operated from the motor, for each 45 signal-arm, connections and circuits for moving the said arms separately and respectively from "danger" and "caution" to "clear," each slot and magnet when locked preventing 50 the return of its respective arm and each restoring device restoring its respective signal-arm to "danger" and "caution" if the slot-magnet, when deenergized, fails to release its signal-arm so as to allow it to return by 55 gravity.

60 3. In a signal, the combination with a semaphore, having a "danger" and a "caution" arm, counterweighted so as to have a bias respectively to the "danger" and "caution" 65 positions, and a motor, of a slot, a slot-magnet, a restoring device operated from the motor, and a restoring-magnet, for each signal-arm, connections and circuits for putting the slot-magnet of one of said arms and the motor 70 in circuit to drive the said arm from the "danger" position to "clear," and for putting the motor out of circuit when the said arm arrives at "clear," for putting the slot-magnet of the other arm and the motor in circuit to drive the said other arm from the "caution" position to "clear," and for putting the motor out of circuit when the said other arm arrives at "clear"—each slot and magnet when locked 75 preventing the return of its respective arm—for putting the two slot-magnets out of circuit to allow the arms to return to the "danger" and "caution" positions respectively by gravity, and for putting the two restoring-magnets and the motor in circuit, each restoring 80 device restoring its respective signal-arm to "danger" or "caution" if the slot-magnet fails, when deenergized, to release its signal-arm so as to allow it to return by gravity.

4. In a signal, the combination with a semaphore, having a "caution" and a "danger" arm, counterweighted so as to have a bias respectively to the "caution" and "danger" positions, and a motor, having a non-reversible armature, and rotating in one direction only, of a slot, a slot-magnet, a restoring device operated from the motor, and a restoring-magnet, for each signal-arm, connections and circuits arranged so that when the slot-magnet of the "danger" arm is energized, the rotation of the motor moves the said arm from the "danger" position to "clear," and whereby the continued rotation of the motor when the magnet of the "caution" arm is energized, moves the said "caution" arm from "caution" to "clear," each slot and magnet when locked preventing the return of its respective arm, and each restoring device restoring its respective arm by the further rotation of the motor if the slot-magnet fails, when deenergized, to release its signal-arm so as to allow it to return by gravity.

5. In a signal, a driving-gear, a driving-pinion engaging with a rack of the signal-rod, a slot mounted on the driving-pinion comprising a magnet, an armature, an escapement-lock, a primary locking device, an intermediate member forming a double locking means from the armature to the escapement-lock when the magnet is energized, means carried by the driving-gear for engaging with the primary locking device to cause the armature to contact with the magnet and the escapement-lock to be locked and for subsequently engaging with the escapement-lock thereby turning the pinion a certain distance moving the signal from "danger" to "clear," the arrangement being such that the means carried by the driving-gear releases itself from the escapement-lock when the signal has attained this position, and retaining means for preventing the return of the signal to "danger" so long as the magnet remains energized and to maintain it in the position to which it has been carried.

6. In a signal, a driving-gear, a driving-

pinion placed eccentric of same and engaging with a rack of the signal-rod, a slot mounted on the pinion comprising a magnet, an armature, an escapement-lock, a primary locking device, an intermediate member forming a double locking means from the armature to the escapement-lock when the magnet is energized, and a retaining-lock, a pin carried by the gear to engage with the primary locking device to cause the armature to contact with the magnet and the escapement-lock to be locked and for subsequently engaging with the escapement-lock thereby turning the pinion a distance equal to one-half of a revolution thereby moving the signal from "danger" to "clear," the pin escaping past the retaining-lock owing to the eccentricity of the pinion with relation to the gear when the signal has attained this position, a notched standard to engage with the retaining-lock to prevent the

return of the signal to "danger" so long as the slot-magnet is energized and for maintaining it in the position to which it has been carried.

7. In a signal, the combination of a gear, a signal-rod having a rack, a pinion engaging with the said rack, a restoring-lever pivoted to the pinion, means carried by the gear for engaging with the restoring-lever, a spring normally holding the lever out of the path of the means carried by the gear, and a magnet for moving the lever into the path of the said means when energized.

Signed at New York this 11th day of October, 1902.

JOHN MILLAR.
